UNITED STATES PATENT OFFICE.

JACOB B. CURRIER, OF LOWELL, MASSACHUSETTS, ASSIGNOR TO THE CURRIER TELEPHONE BELL COMPANY, OF MASSACHUSETTS.

ELECTRIC CALL.

SPECIFICATION forming part of Letters Patent No. 425,594, dated April 15, 1890.

Application filed October 17, 1881. Serial No. 43,989. (No model.)

To all whom it may concern:

Be it known that I, JACOB B. CURRIER, of Lowell, in the county of Middlesex and State of Massachusetts, have invented certain new and useful Improvements in Electric Calls and the Apparatus Connected therewith, of which the following is a specification.

My improvements relate to the electric calling apparatus patented to me August 30, 1881, by Patent No. 246,374; and they consist in placing the magnet and bell in a novel position relatively to the bell-hammer and modifying the construction of the latter, as hereinafter described, whereby I am enabled to make the calling-instrument operate more surely and effectively in calling any particular bell; secondly, in providing the calling-instrument with an automatic circuit-breaking mechanism when stationary to save battery-power and render the operation of the bells more effective; thirdly, in providing the calling-instrument with a cam-shaped drum or cylinder or equivalent crank-arm for enabling me to lengthen and shorten the vibrating caller between any two bell-hammer lengths to the length of the one to be operated over the line by a substantially equal amount of rotation on its cam or crank axis to that required to adjust it between any other two bell-hammer lengths; fourthly, in attaching to the axis on which the cam or crank of the calling-instrument moves a detent-lever and providing the dial with a series of holes, into which the detent fits, as hereinafter described, to cause the crank-arm or drum to be brought and held in exactly proper position, and thus readily give the vibrating caller the proper length to call the desired station on the circuit.

In the drawings, Figure 1 shows an electrical circuit provided with a calling-instrument and a series of individual bells, the caller having part of its face broken away to show its internal construction. Fig. 2 represents a modification of the calling-instrument with the face of its case partly broken away to show its internal mechanism. Fig. 3 shows the face of the calling-instrument complete ready for operation. Fig. 4 represents the individual bell of my improved construction.

Fig. 5 is an edge view of the caller in its case, as shown in front view in Fig. 3.

The general system of individual bells here referred to is shown and fully described in my above-named Letters Patent, and its general operation need not be here redescribed.

On the circuit, 1^a, 2^a, and 3^a represent three different stations provided with call-bells, having each a different length of sprung-tongue to give it individual action with a proper broken or undulatory current. The calling apparatus is placed at the central station 4^a.

O are the ground-connections at each end of the circuit. 65

L is the battery.

B is the bell. A is its magnet.

H is the bell-hammer. The hammer is placed, according to my improvement here claimed, between the magnet A and bell B, 70 instead of having the magnet and bell on the same side of it. This arrangement is a great improvement on my former one for this reason.

In my former patent I have explained how 75 a spring-hammer enables itself to be kept nearer to the vibrating time of the broken electric current generated by the vibrating spring g of the collar than is possible with a free swinging pendulum, thus causing the 80 bell-hammer to continue to strike the bell when once set in action instead of being thrown out of striking time by rebounding from the bell, as a free swinging pendulum is. By experiment, however, I have discovered 85 that while the spring-hammer in sounding the bell keeps the time of its own vibration near enough to that of the vibrative current to thus continue to strike the bell, it does not with my former construction exactly keep 90 such time, and consequently some part of the electric force is wasted and the force of the blow of the hammer on the bell is thus diminished perceptibly. Suppose, for instance, a spring bell-hammer normally vibrating two 95 hundred and forty times per minute is used with my former arrangement. Taking the hammer in a state of rest, I am obliged to set the vibrating caller g so that it will vibrate substantially two hundred and forty times 100

- per minute in order to set the hammer in motion by the vibrative current generated by the caller. Under the action of this current the bell-hammer will be set in vibration at its normal rate and constantly increase its swing until it strikes the bell. In repeated striking of the bell the vibrating hammer will have its rate increased somewhat above two hundred and forty times per minute, and its vibration thus varying from that of the current generated by the caller, which remains constant, part of the electric force is expended in acting against the spring while it is farthest away from the magnet and least susceptible to its influence, and is accordingly wasted.
- My present arrangement overcomes this difficulty in the following manner, and produces a louder alarm with the same volume of electric force. The magnet being on the opposite side of the hammer from the bell, the rebound of the hammer from the first blow on the latter sends it with accelerated motion nearer to the magnet and directly into its strongest attractive force, giving it sufficient power to control the motion of the hammer. The magnet therefore holds onto the hammer and detains it at the farthest point of its rebound from the bell until the current is broken and the hammer released to spring forward against the bell. This operation is constantly repeated and the hammer kept vibrating in time with the make and break of the current instead of out of that time, thus making the motion of the bell-hammer and vibrating caller *g* coincide while the bell is being sounded. In order to aid this action of the magnet, I make the armature of the hammer and its striking part substantially in one piece and make the flexible part of it entirely between the hammer-armature and its point of support. This construction gives the magnet greater leverage over the striking-hammer, and at the same time a larger mass of soft metal to act upon, thereby increasing its efficiency. It also diminishes the amount of weight to be carried by the spring and enables me to use several more bells on a circuit at higher rates of vibration than was before practicable.
- My second improvement consists in so placing the lever *m* and its spring *n* that the battery-circuit will be connected with the line only when the vibrating caller is in operation, and will be connected then only through the contact-point *k* of the vibrating caller. The caller will thus automatically break the circuit at the instant that the lever is released. This prevents induced currents of electricity from flowing over the circuit and the bell-hammer armature from clinging to its electro-magnet. The importance of this is considerable.
- In the caller shown in Fig. 1, *g* is the line connected with the battery which is connected to the caller-actuating lever-stud *p*. The metal arm *o* of the wooden lever *m*, which actuates the vibrating caller, comes into contact with the metal stud *r* when the lever *m* is moved

out of the way of the vibrating caller, and the electric current will pass to the stud *r* and from it to the insulated contact-screw *k*, against which the vibrating caller-spring *g*, of metal, comes in contact to make and break the circuit by the current passing through the spring and its metal clip to the line leading to the bells. When, however, the vibrating caller-actuating lever is released by the operator, the spring *n* brings the arm *o* into contact with the stud *v* and cuts the screw *k* out of the battery-circuit. Suppose we have an electrical circuit with a bell at station 1 vibrating five hundred times per minute and one at station 2 vibrating five hundred and fifty times. If after using station 1 bell its hammer is immediately released from magnetic influence by the breaking of the circuit, I can therefore immediately call No. 2 bell; but if the circuit be not thus broken there is a liability of sounding No. 1 bell in calling No. 2, because the hammer-armature may cling to its electro-magnet until released by the break first made in calling the next bell. The automatic breaking of the circuit in the caller, as described, sensibly overcomes this difficulty and enables me to place more bells on a circuit.

Instead of the cylindrical wheel or drum *b* shown in the patent before referred to for lengthening and shortening my vibrating caller *g*, I have adopted a cylinder rotating on the axial stud, which is provided with a crank-arm *s*, to which the upper end of the spring of the caller is attached, which with each forward movement of the index-hand attached to the cylinder will shorten the spring vibrating part of the caller less than did the last preceding movement of the index-hand through an equal space over the dial-face. Another form to accomplish this is shown in Fig. 2, in which is a cam-shaped cylinder which constantly diminishes the amount which it shortens the vibrating caller, as it continues to shorten it in proportion to a given amount of rotation. The reason of this construction is that it requires a greater shortening of the vibrating caller to adapt it to two bells adjacent in rate of vibration in the lower speeds than it does in the higher. For instance, suppose the lowest bell-hammer in vibration to be two hundred and forty times per minute and the next greater to be two hundred and ninety times per minute. It will require a much greater shortening of the length of the caller between their lengths than it would between the lengths of two bell-hammers when the lowest vibrated one thousand times per minute and the next highest vibrated one thousand and fifty times; hence I proportion the cam-shortening cylinder or crank-arm so that with an equal amount of rotation on its axis it will so shorten the vibrating caller as to adapt it to two consecutive bells whether vibrating at the higher or lower speeds. This enables me to move the dial-hand which is attached to the axis of this cam or arm over an equal space to call

any bell after calling the next one below it in vibration.

My fourth improvement consists in attaching to the index-hand b' of the cylinder b an extension or prolongation b'' on the opposite side of its axis from the hand and providing this prolongation with a pin or detent projecting inward and made to accurately fit a series of holes in the dial-face 1' 2' 3', &c. 5 These holes are so placed that this prolongation of the pointer, being elastic, springs the detent into the hole at the exact point required to adapt the length of the vibrating caller g to some one of the bell-hammers on the line. This not only saves time and care on the part of the operator in calling any bell, but it is valuable in setting the index to call a bell having its hammer vibrating on a high number—as, for instance, eleven hundred vibrations per minute—because the higher the number of vibrations per minute the greater the accuracy required in lengthening or shortening the vibrating caller g to the exact extent necessary to operate the bell-hammer 25 vibrating at that rate. By means of the holes 1' 2' 3', &c., and their detent I am enabled to attain the greatest exactitude and celerity in this respect, where it is so important. The detent also locks the cylinder in this exact 30 position and prevents it from being moved by accident.

What I claim as new and of my invention is—

1. The combination of an electric circuit, a vibrating circuit-breaking mechanism there- 35 in arranged to make and break the circuit regularly and automatically at a predetermined rate of vibration, and an alarm mechanism in said circuit, consisting of magnet A, bell B, and the vibrating striker H, located 40 between them, provided with an armature and arranged to automatically vibrate synchronously with said circuit-breaker, whereby the variation in the rate of vibration of the 45 striker produced by its blow upon the bell will be overcome by the magnet upon the re-

bound of the striker toward it, substantially as described.

2. The combination of an electric circuit, a vibrating circuit-breaking mechanism there- 50 in arranged to make and break the circuit regularly and automatically at a predetermined rate of vibration, and an alarm mechanism in said circuit, consisting of magnet A, bell B, and the vibrating striker H, having its 55 striking part and armature formed of one rigid piece of metal and its elastic part entirely between the latter and its point of support, said striker being arranged to automatically vibrate synchronously with said circuit- 60 breaker, whereby the production of secondary and interfering vibrations between the armature and striking part of the striker by its blow upon the bell and the consequent disturbance of its synchronous vibration are 65 avoided, substantially as described.

3. The combination of an electric circuit, the vibrating circuit-breaker g , having its spring portion adjusted to make and break the circuit automatically at a predetermined 70 rate of vibration and to be held in position to break the circuit when its vibration ceases, and two alarm mechanisms in said circuit, one of which has the spring portion of its striker adjusted to automatically vibrate syn- 75 chronously with said rate of vibration of the circuit-breaker and the other of which has the spring portion of its striker adjusted to vibrate at a substantially different rate of vi- 80 bration not affected by the circuit-breaker, substantially as described.

4. In combination with the circuit of individual call-bells, the caller g and its arm b , provided with the arm b'' and its detent, and the corresponding holes 1' 2', &c., placed to 85 adjust the caller to the length to call one or more of said bells, substantially as described.
